UNITED STATES PATENT OFFICE

2,440,773

BRICK SIDING CUTTER

John V. Hostetter, Berwyn Heights, Md.

Application February 8, 1946, Serial No. 646,403

4 Claims. (Cl. 164—39)

1

This invention relates to cutting machines for sheet material, and more particularly to a cutting machine for imitation brick siding sheets.

A main object of the invention is to provide a novel and improved cutting machine for brick siding sheet material or the like, of very simple construction which is inexpensive to build and very easy to operate.

A further object of the invention is to provide an improved cutting machine for sheet material of the type employed for imitation brick siding and the like, wherein the exterior surface of the sheet material is substantially rigid or semirigid and the bottom surface of the material is more or less porous, fibrous or deformable in nature, such as a bottom surface of "Celotex" or the like, the machine being adapted to provide a flat steady support for the material being cut and being provided with means for accurately perforating the rigid exterior surface of the sheet along a desired line of cut.

Further objects and advantages of the invention will become apparent from the following description and claims, and from the accompanying drawings, wherein:

Figure 1 is a plan view, partly in cross-section, of a cutting machine constructed in accordance with the present invention.

Figure 2 is a detail cross-sectional view taken on line 2—2 of Figure 1.

Figure 3 is a side elevational view, partly in cross-section, of the cutting machine of Figure 1.

Figure 4 is a detail cross-sectional view taken on line 4—4 of Figure 3.

Figure 5 is a detail view of the cutting wheel and its support as employed in the cutting machine of Figure 1.

Referring to the drawings, 11 designates a table of suitable size and generally rectangular in shape adapted to receive and support a slab of imitation brick siding or similar sheet material during the cutting thereof. Secured to table 11 adjacent one corner thereof is a bracket member 12 formed with a pair of spaced parallel lugs 13, 13 receiving a bolt 14. Pivotedly mounted on bolt 14 between lugs 13, 13 is an arm 15 extending toward the opposite side of table 11 and inclined with respect thereto at an angle of about 45°, although other angles may be employed within the spirit of this invention. Arm 15 is formed with a vertical rib 16 to increase its rigidity. The end of arm 15 is recessed to form a pair of horizontal, spaced lugs 17, 17 and adjustably secured therein is a bifurcated bolt member 18.

2

Rotatably secured between the depending fingers of member 18 is a cutter wheel 19.

Secured below the surface of the table adjacent bracket 12 is a vertical bolt member 21 which projects upwardly through the table surface and through arm 15. Pivotedly secured to the top end of bolt member 21 is a lever member 22 formed with a cam portion 23 adapted to cooperate with the upper horizontal surface of the main body portion of arm 15. Lever member 22 is further formed with a laterally offset handle portion 24. A coil spring 25 encircles bolt member 21 and bears between a pin 26 extending through the lower portion of said bolt member and the under surface of arm 15, biasing said arm to a raised position. When arm 15 is in its depressed position, as shown in Figures 1, 2 and 3, cutter wheel 19 is disposed closely adjacent the surface of table 11. When lever 22 is rotated to a substantially vertical position, spring 25 raises arm 15 so that cutter wheel 19 is spaced a substantial distance above table 11, providing clearance for the rapid insertion or removal of sheet material.

Rotatably supported below the surface of table 11 in a transverse vertical plane which includes cutter wheel 19 is a shaft 27 provided at the end thereof adjacent cutter wheel 19 with a pair of circular saw blades 28, 28 parallel to and spaced a short distance on either side from the plane of cutter wheel 19. The upper peripheral portions of saw blades 28, 28 project through slots 29 provided therefor in the surface of table 11 and said peripheral portions project a slight distance above the plane of the table. The teeth of the saw blades are arranged to engage the bottom fibrous or deformable surface of a sheet of siding material and to move said sheet into cutting engagement with cutter wheel 19 responsive to rotation of shaft 27.

40 The other end of shaft 27 has mounted thereon a bevel gear 30 which is in mesh with and is adapted to be driven by a bevel pinion gear 31 carried on a shaft 32 journalled in table 11 and provided with an external crank handle 33. 45 When crank handle 33 is rotated, torque is transmitted through the bevel gears to shaft 27, causing toothed blades 28, 28 to rotate. If a sheet of siding material is placed on table 11 with its porous or fibrous side down, the toothed blades 50 will engage said fibrous or porous side and feed the sheet against cutter wheel 19, assuming arm 15 to be in its depressed position. Cutter wheel 19 will indent or shear the rigid or semi-rigid upper face of the siding material along the desired line of feed and upon removal of the

sheet the partly severed portions thereof may be readily separated.

An access door 24 is provided in the side panel of table 11 adjacent blades 28, 28 to permit convenient removal and replacement of the blades when required.

While a specific embodiment of a cutting machine for imitation brick siding material or the like has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A cutting machine for sheet material comprising a table of substantially rectangular shape, an arm overlying said table and extending across the latter towards an opposite edge thereof, said arm being pivotally secured to said table adjacent one corner thereof, a cutter wheel located adjacent said edge and carried by said arm, said arm being movable to a position wherein said cutter wheel is closely adjacent the plane of the table, a plurality of toothed wheels mounted on a horizontal axis below the table surface, the upper peripheral portions of said wheels projecting through the table surface, said wheels being located in planes parallel to and closely adjacent the plane of the cutter wheel, and means for simultaneously rotating said toothed wheels.

2. A cutting machine for siding material comprising a table, an arm adjustably secured to said table adjacent one corner thereof and overlying

said table, said arm extending toward an opposite edge of the table in a direction inclined with respect to said opposite edge at an angle less than 90°, a cutter wheel carried by said arm adjacent said opposite edge, said arm being movable to a position wherein said cutter wheel is closely adjacent the surface of the table, a pair of toothed wheels mounted on a shaft journaled below the table surface, the upper peripheral portions of said wheels projecting through the table surface, said wheels being located in planes parallel to and closely adjacent the plane of the cutter wheel on either side thereof, and means for rotating said shaft.

15 3. The structure of claim 2, and wherein said arm is inclined at an angle of 45° with respect to said opposite edge of the table.

20 4. The structure of claim 2, and wherein said arm is biased to a raised position wherein substantial clearance is provided between said cutter wheel and the table surface.

JOHN V. HOSTETTER.
